G. S. HALE,
GASOLENE STRAINER,
APPLICATION FILED DEC. 13, 1916.

Patented June 12, 1917.

UNITED STATES PATENT OFFICE.

GEORGE SAMUEL HALE, OF TEKOA, WASHINGTON.

GASOLENE-STRAINER.

1,229,608.

Specification of Letters Patent. Patented June 12, 1917.

Application filed December 13, 1916. Serial No. 136,619.

To all whom it may concern:

Be it known that I, GEORGE SAMUEL HALE, a citizen of the United States of America, and a resident of Tekoa, county of Whitman, 5 State of Washington, have invented certain new and useful Improvements in Gasolene Strainers, of which the following is a full and clear specification.

The object of this invention is to provide 10 a simple gasolene strainer for attachment especially to those gasolene engines which are employed on motor vehicles, launches, etc., and the invention consists of certain novel features of construction hereinafter 15 described and claimed.

In the drawing, the figure represents a vertical sectional view of a preferred form of the device.

In this drawing, *a* designates the inlet pipe 20 of the device which is screwed into a nipple *b* formed on the upper or cap member *c* of the chamber. The inlet pipe extends down into the chamber and is provided with a downwardly-facing shoulder *d* near its inner 25 end. A gasolene outlet pipe *e* is connected with a central chamber *f* in the upper part of the cap *c*, this chamber surrounding the reducer extension *g* of the inlet pipe.

An annular downwardly-facing shoulder 30 *h* is formed on the interior of the cap *c* in the same horizontal plane with the aforesaid shoulder *d*, and clamped up against these shoulders *d* and *h* is a felt strainer disk *i*, the clamping means in the present instance being 35 a cylindrical extension of sediment cup *j* which is screwed up into the cap *c* so that its annular edges are made to engage the opposite marginal edge of said disk. The lower end of this cup is tapered and rounded 40 downwardly so as to collect sediment in its bottom at a distance from the inlet and strainer disk. Foreign substances that are collected in this cup may be discharged through a discharge opening in the bottom 45 of the cup, this opening being controlled by a suitable valved pipe connected to the cup.

The gasolene enters the strainer through the pipe *a* whose discharge mouth is flush with the underside of the strainer, and then 50 passes up through the porous disk *i* into a chamber formed between the same and the top of the cap, and thence into the annular chamber *f*, whence it passes to the carbureter of the engine. All foreign substances, including sand, dirt and water, settle by 55 gravity to the bottom of cup *j*, the solid

foreign matters being strained out of the gasolene by the strainer disk.

It has been found to be important to end the inlet pipe flush with the underside of the 60 strainer disk, owing to the fact, learned from practical tests, that if the gasolene is supplied to the chamber at a point the slightest distance below the underside of the disk, air will be trapped in a thin film between the 65 felt disk and the mouth of the inlet and will stop the flow of gasolene through the filter. Therefore, by ending the inlet flush with the underside, air can escape back through the 70 inlet until the underside of the disk is flooded. This serious objection applies to gravity feeding devices.

It will be observed that the inlet and outlet pipes may be arranged differently without departing from the spirit of my invention. 75

It will be observed that a feature of importance in my device lies in the fact that the strainer disk faces downwardly, and that it has no meshes, such as wire gauze presents, to catch and hold foreign solid substances, so 80 that at all times the strainer will be clean and fully effective. It will be also observed that the fact that the strainer disk faces downwardly is important when this device is 85 used on vehicles, as in that case the vibration of the vehicle will tend to shake off any substances that collect on the under face of the disk. It will be also observed that the disk may be quickly and readily removed for 90 cleaning and renewal. It will be also observed that water that may be carried by the gasolene will be collected in the bottom of the cup and that it will not pass over through the disk with the gasolene unless the cup is filled up to the lower face of the 95 porous disk. It will be understood, of course, that the operator will clear the cup of sediment and water from time to time by merely opening the valve in the exit thereof.

It is important also that a felt strainer be 100 used in my device, as I have found in practice that a wire strainer will entangle and hold the foreign matters and thus clog the meshes; and it is further important that this filtering disk shall be readily removable 105 from the apparatus in order to occasionally clean it of the finer foreign particles that eventually work into it. In order to make this disk removable readily, I utilize the upwardly extending annular flange on the cup 110 *j* to clamp its edge against the shoulders *h* formed on the wall *c* and also against the

downwardly facing shoulder *d* on the central supply pipe. With this manner of fastening the disk, it is unnecessary to employ a fastening means at the center thereof, since the 5 clamping action of the edge of the disk will be sufficient to hold it up against shoulder *d*, and it will be observed that to remove the disk it is simply necessary to unscrew the cup *j*.

10 The nature and scope of the invention having been thus indicated and its preferred embodiment having been specifically described, what is claimed as new is:

15 A device of the class set forth, comprising a cup member, a chambered cap member removably secured thereto, and a felt straining disk, one of said members being provided

with an internal annular shoulder against which one face of the outer margin of said straining disk engages, and the other member being provided with an annular edge which is adapted to be screwed into the first mentioned member to engage the opposite marginal face of said disk to clamp the same in position against said shoulder, an outlet pipe connected with the interior of said cap member, and an inlet pipe having its discharge mouth flush with the underside of said disk and adapted to supply fluid to said cup member.

20 25 30 In testimony whereof I hereunto affix my signature.

GEORGE SAMUEL HALE.
